US00D860252S

(12) **United States Design Patent** (10) Patent No.: **US D860,252 S**
(45) Date of Patent: **** Sep. 17, 2019**

(54) **DISPLAY SCREEN OR PORTION THEREOF WITH ICON**

(71) Applicant: **RADIANT INNOVATION INC.**,
Hsinchu (TW)

(72) Inventors: **Yung-Chang Chang**, Hsinchu County
(TW); **Feng-Lien Huang**, Hsinchu
(TW)

(73) Assignee: **RADIANT INNOVATION INC.**,
Hsinchu (TW)

(**) Term: **15 Years**

(21) Appl. No.: **29/653,416**

(22) Filed: **Jun. 14, 2018**

(51) LOC (12) Cl. **14-04**

(52) U.S. Cl.

USPC **D14/489**; D14/492

(57) **CLAIM**

The ornamental design for a display screen or portion thereof with icon, as shown and described.

DESCRIPTION

FIG. 1 is a front view of a display screen or portion thereof with icon showing our new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof; and,

FIG. 8 is a front view of an eighth embodiment thereof.

The dot-dash broken lines in the figures show a display screen or portion thereof, and form no part of the claimed design. The dashed broken lines in FIGS. 5-8 show a graphical user interface, and form no part of the claimed design.

1 Claim, 8 Drawing Sheets
